UNITED STATES PATENT OFFICE.

WILLIAM HENRY STANDISH, OF REEDS SPRING, MISSOURI.

DAM AND TUNNEL.

1,280,573

Specification of Letters Patent. Patented Oct. 1, 1918.

Application filed December 8, 1917. Serial No. 206,219.

To all whom it may concern:

Be it known that I, WILLIAM H. STANDISH, a citizen of the United States, and a resident of Reeds Spring, in the county of Stone 5 and State of Missouri, have invented certain new and useful Improvements in Dams and Tunnels, of which the following is a specification.

This invention relates to improvements in 10 dams and particularly to means to permit the most efficient utilization of the water held by the dam during dry periods and to lessen the liability of damage being done to the dam foundations at flood times.

15 Another object is to reduce the liability of washouts at the dam foundations.

Another object is to provide means for utilizing the water for power purposes in a most efficient manner and to discharge the 20 used water down stream with a sufficient drop to provide the requisite nozzle pressure at the inlet ports of the power machines, as, for example, turbines.

Other objects and advantages of this invention will become apparent as the nature 25 of the invention is better understood, it being clear that changes in form, proportion and minor details of construction may be resorted to without departing from the 30 spirit of the invention or sacrificing any of its advantages.

In carrying out my invention I preferably arrange a dam across the stream consisting of a solid wall, the base of which may be 35 approximately twice its height with the sides of the wall sloping inwardly toward the top. The dam may be formed with a tunnel or tunnels at the time of its construction and in actual practice I prefer to construct the dam with two tunnels, one at each 40 end, the openings for the tunnels penetrating through the wall and the tunnels continuing down stream preferably with a gradual drop until they discharge into wa- 45 ter chambers which may be arranged trans- versely of the tunnels and which may have outlet openings discharging into the requisite number of turbines or other hydraulic motors whereby the pressure energy may be 50 converted into kinetic energy. Water cham- bers are also provided with valued discharge openings at their ends whereby the water may be discharged around the turbines and into the stream when desired.

55 The upstream ends of the tunnels may be closed by suitable water gates controlled

from above the water level and the openings of the tunnels may be protected by screens to prevent the introduction of obstructing matter into the tunnels, the purpose of the screens being to maintain the tunnels clear at all times. 60

In the drawings:

Figure 1 is a view partly in plan and partly in section of a dam and its appurtenances constructed in accordance with my invention. 65

Fig. 2 is a fragmentary sectional view through the dam, the tunnel being fragmentarily shown in elevation; 70

Fig. 3, is an enlarged front view of one of the tunnels showing the gates and part of the lattice of screen for protecting the tunnel; 75

Fig. 4 is an enlarged fragmentary side elevational view of one of the tunnels;

Fig. 5 is a view partly in plan and partly in section of a tunnel;

Fig. 6 is a cross sectional view through the water discharging chamber; and 80

Fig. 7 is an end view of one of the water discharging chambers.

Referring now to the drawings by numerals of reference, 10 designates a dam wall made solid of concrete or some other suitable material and preferably resting upon bed rock. Extending through the dam and formed integrally therewith are tunnels 11 and 12, in the present instance shown as being positioned, one at each end of the dam 90 and as both tunnels are substantially alike, I will describe but one of them. The inlet for each tunnel is on the upstream side of the dam wall, the tunnel being positioned at the base thereof and having inlet 13 reinforced with a gate frame consisting of the uprights 15, 16, 17 and 18 to constitute guides for the gates 19, 20 and 21. The gates are connected to elevating rods 22, 23 and 24 respectively each of which is provided with an elevating handle or wheel 25 whereby the gates may be raised and lowered in their frame. Across the entrance to the tunnel I provide a baffle in the form of slats 26 which constitute a screen to eliminate the liability of extraneous matter such as brush, bows, logs and the like from entering the tunnel and clogging it. This screen, however, in no wise interferes with the discharge of the water through the tunnel. 100 Each tunnel continues through the solid wall down stream preferably with a gentle slope 110

until it empties into a turbine water-distributing chamber 27. This chamber extends transversely of the tunnel and has a valved end 28 adapted to be closed by a valve 29 on the stem 30 and operated by the handle 31 in a well known manner whereby the water may be discharged at the end of chamber 27, instead of escaping through the outlets 32 of which there may be a number 10 equal to the number of turbine discharge nozzles and may be controlled by the valves on the rods 33 there preferably being a valve for each nozzle so that the desired number of turbines may be put in operation or cut 15 out if desired. On the sides of the stream between the dam and the power house I prefer to arrange bank retaining walls 34 and 35 the length of which are coextensive with the lengths of the tunnels so as to provide a 20 zone within which workmen may readily repair the dam and its appurtenances.

While I have shown two tunnels arranged one at each end of the dam wall, I do not desire to be limited to this construction as 25 under certain conditions, I may employ only one tunnel, or, multiply this number to conform to the conditions present. It will be apparent that inasmuch as tunnels are formed substantially as integral parts of 30 the dam wall constructed at the time that the dam is put up, that the advantages accruing from this invention may be provided in a most inexpensive manner and it will be further apparent that the impounded 35 water may be efficiently used for industrial purposes even at low levels because the tunnels are preferably at the bottom of the dam wall. Attention is also called to the fact that the water may be utilized for in- 40 dustrial purposes or to augment the level down stream without the liability of the tunnel becoming clogged by debris or dam- 45 aging the power machinery. In actual practice the tunnel may be reinforced by up- rights, rafters or the like or by any other suitable means and it is to be understood that I prefer to arrange the uprights of the 50 gate frame in sockets below the floor of the tunnel so that the water behind it and the debris will be held back from entering the tunnel.

In constructing the wall 10 I prefer to follow the engineering practice of providing the wall at the bottom with a width approxi- 55 mately twice that of its height so that the material in the solid dam for each lineal foot across the stream will be equal to the square of its height.

Mountain rivers sometimes rise many feet

above their normal stage and if obstructed 60 by a dam will cut back into the bank over the dam to a point beyond its end and then downward until a new channel is formed around the end of the dam that makes the dam useless when the river returns to normal stage. By having the tunnels next to the banks of the river and locating concrete barriers over the peak and lower side of the dam and extending upwardly above the high water limit, and placing say, ten feet 70 of concrete facing on top of the tunnels and against the banks below the dam as far as the power house, flowage will be carried so far down the river as to prevent the water cutting around the end of the dam or undermining it on the lower side, and this will be done with about one-third of the expense 75 that would be involved in walling the banks.

These tunnel discharges leave empty lakes of a capacity sufficient to arrest the excess 80 water of sudden rises until every dam pondage is refilled. During normal flowage of the river, the bed will be dry, and during flood stages, the general slope of the dam will carry over rafts between the tunnels 85 and enable fish to ascend and descend the river.

With the construction herein described, the main dam and the outside of the side walls and tunnels can be reconcreted without the expense for cribbing and without stopping power of machinery while repairs 90 are going on.

I claim:—

1. A dam having a wall, a down stream 95 water delivery chamber for power mechanism below the dam, a tunnel extending through the dam with its inlet at the upstream side of said wall and discharging into the water delivering chamber, said chamber 100 being disposed transversely of the tunnel and having a discharge outlet at one end and turbine water delivering nozzles and valves for said discharge outlet and said nozzles.

2. A dam, a downstream water delivery chamber for power mechanism below the dam, a tunnel extending through the dam, with its inlet at the upstream side of said 105 dam and discharging into the water delivery chamber, said water delivery chamber having a by-pass outlet at one end, and water delivery nozzles and valves for said by-pass outlet and said nozzles.

The foregoing specification signed this 115 28th day of November, 1917.

WILLIAM HENRY STANDISH.
